SMOKING PIPE

Marion Plesh, Represa, Calif.

Application May 25, 1945, Serial No. 595,668

2 Claims. (Cl. 131—222)

1

This invention relates to a new and useful improvement in smoking pipes and the like, the principal object being to provide a smoking pipe or a cigarette holder wherein means is provided for cooling the smoke before reaching the smoker's mouth.

Another important object of the invention is to provide a smoking pipe wherein a hollow walled bowl is provided for conducting off heat radiating from the smoking chamber, to the end that the outside of the bowl will not be hot in the hands of the smoker.

Still another important object of the invention is to provide a smoking pipe which takes care of cooling the bowl, cooling the smoke for its passage through the stem of the pipe and before it reaches the mouth of the smoker, together with provision for removal of excess nicotine-laden moisture, wherein the various parts that go to obtain these different results are separate and separable as regards to structure, to the end that these parts can be taken apart whenever desired for the purposes of repairs or replacement and also for the thorough cleaning thereof.

Other objects and advantages to be attained will hereinafter more fully appear in the following description.

In the illustrative but non-limiting exemplification of the invention,

Figure 1 of the drawings is a vertical longitudinal sectional view through a pipe structure;

Figure 2 is a top plan view of the base stem and bit or mouth piece assembly detached from the pipe bowl, the base stem being in longitudinal section at a 90° angle from that of Figure 1 and the nipple extension of the bit or mouth piece being in fragmentary longitudinal section;

Figure 3 is a vertical transverse section taken on the line 3—3 of Figure 1;

Figure 4 is a fragmentary view partly in top plan and partly in horizontal section taken on the line 4—4 of Figure 1.

Referring now to the drawings in detail and wherein like numerals designate like parts, it can be seen that the numeral 5 denotes, generally, a bowl, the numeral 6 a base stem to which the bowl is detachably secured, and the numeral 7 a bit or mouth piece fitted detachably to the base stem. The base stem 6 is internally screw threaded along its upper portion from its bowl end to its opposite end for receiving the correspondingly externally screw threaded, elongated nipple extension 8 of said bit or mouth piece 7,

2

the lower portion of the stem being smooth bored, as clearly shown in Figures 1 and 3.

The bit or mouth piece 7 is provided with an axial smoke bore or duct 9 extending longitudinally from its outer end and terminating a short distance within the nipple extension 8, as at 10 (see Figures 1 and 2).

The externally screw threaded circumferential portion of the nipple extension 8 is provided with a plurality of longitudinal smoke duct grooves 11 communicating transversely at their opposite ends so as to constitute a reversible continuous passageway extending substantially from end to end of said nipple extension. That is to say, the ends of the grooves terminate near the opposite ends of the nipple extension 8 and they are alternately connected in staggered relationship so that the smoke drawn from the bowl 5 travels for a considerable length, reversely, back and fourth from substantially end to end of the nipple extension 8 and within the internally screw threaded bore of the base stem 6.

One of the aforesaid longitudinal, partially circumferential smoke duct grooves 11 starts at or about the place, designated at 12 (see Figure 2) and terminates adjacent the base of the nipple extension 8, as at 13, whence it is turned at substantially a right angle, as at 14, and joins communicably with a second longitudinal groove 15 located at the side of the nipple extension at substantially an angle of ninety degrees from the groove 11. This groove 15 extends to the vicinity of the bowl end of the nipple extension 8, where it is cross-connected by a semi-annular transverse short groove 16 to the end of a third longitudinal groove 17 along the side of the nipple extension 8 diametrically opposite the groove 15. The opposite end of the groove 17 terminates communicably with the end 10 of the smoke duct 9 through a short angular cross passage 18.

It is here noted, that the smoke from the bowl 5 enters the end portion 12 of the first longitudinal smoke duct groove 11 and then passes forwardly through said groove 11, thence across the arcuate connecting passage 14 into the second longitudinal groove 15, through which latter groove the smoke continues its travel rearwardly through said groove 15 to the rear-positioned arcuate cross passage 16 to and through the third longitudinal smoke duct groove 17, whence the smoke passes through the cross passage 18 and into and out through the axial smoke duct 9 in the bit or mouth piece 7.

The nipple extension 8 is cut away and flattened on its under side, as at 19, from a point

20 adjacent the base of said extension where it joins the bit or mouth piece 7 to the free end of the nipple (see Figure 1). This cutting away and mutilation of the nipple extension 8 on the under side thereof produces with smooth bored lower portion of the stem 6 an elongated space 21 which space 21 is connected at its forward end communicably with the smoke duct groove 17, as at 18', adjacent where said groove 17 communicates with the smoke duct 9 in the bit or mouth piece 7 through the cross passage 18. Hence, all excess, nicotine-impregnated, moisture coming from the bowl 5 through the smoke duct groove 17 is condensed in the space 21 and is thus trapped and prevented from passing with 15 the desired smoke into the mouth of the smoker.

In order to appreciably increase the capacity of the trap afforded by the said space 21, the cutaway bottom face 19 of the nipple extension 8 is grooved longitudinally, as at 22, medially, parallel with and contiguously below its axis, this groove 22 extending to the rear end of the nipple and being, itself, open-ended. By this provision, not only is the capacity of the nicotine-laden moisture trap 21 greatly increased in capacity and without interfering with the aforesaid provision and arrangement of smoke duct grooves and cross-connections in the nipple extension, but the parts are readily cleaned in their assembled relation as will presently more fully appear. Then, too, the bit or mouth piece 7, with its nipple extension 8 intact therewith, is readily unscrewed and detached from the pipe stem base proper and replaced at will.

At the rear or bowl end of the base stem 6 is 35 an endwise bore which is screw threaded internally to receive a screw plug 23 having a peripherally knurled cap or collar portion 24 which is tightened against the adjacent end of the base stem 6 when the plug is inserted to close the end 40 of the bore in the base stem. Preferably, there is a clearance space 25 provided between the inner end of the plug 23 and the adjacent end of the nipple extension 8. This is primarily intended to prevent contact between the parts 8 and 23 so as not to interfere with the tightening of the bit or mouth piece 7 against the adjacent 45 opposite end portion of the base stem 6.

The bowl 5 is constructed of an outer wall 26 having a bottom 27 formed with air openings 28 therein. The bottom has a central threaded opening therethrough for receiving tightly therein a correspondingly threaded reduced end portion of an axially apertured nipple 29 depending from the bottom of an inner bowl 30. As shown more clearly in Figure 4, the apertures 28 in the bottom of the outer bowl portion are arranged 50 annularly in the bottom 27 adjacent said outer wall 26. The outer bowl member having the outer wall 26 has a kerf-formed boss 31 on the bottom 27 thereof for receiving slidably the tongue-and-groove side portions of the base stem end portion so as to hold the bowl 26 in place on the stem 6, the nipple 29 has a protruding reduced lower end portion which fits snugly in a corresponding registering hole provided thereunder in the adjacent top portion of the base stem 6. Thus, the bowl assembly 5 is readily removable off the rear end of and replaceable on the base stem 6 and the bowl assembly, itself, as readily assembled and disassembled, at will. It is also noted that the hole in the base stem 6 that receives the lower end of the nipple 29 is 55 communicable directly with the end portion 12 75 of the

of the first duct groove 11 in the assembled nipple extension 8.

The upper portion of the inner bowl 30 has an outwardly projected, circumferential, annular shoulder 32 on its top portion, with an annular top flange 33 of said circumferential shoulder 32 overlapping the upper edge of the outer wall 26 of the outer bowl. The circumferential shoulder 32 has openings 34 therein and this shoulder serves to space the inner bowl 30 from the outer wall 26, thus leaving a circulatory air passage 35 between the outer wall 26 and the inner bowl 30. Obviously, as heat radiates from the inner bowl 30 while the pipe is being smoked, air begins to rise in the space 35, with outside air entering the openings 28 and expelling the heated air in the space 35 between the inner bowl 30 and the outer wall 26 through the upper openings 34, thus conducting away the heat which is radiated by the inner bowl 30.

In placing the bowl assembly 5 on the base stem 6 for use, the inner bowl 30 is first unscrewed from the outer bowl 26 and removed therefrom. Then the outer bowl 26 is slid with its kerf-formed bottom boss 31 onto the groove portion of the base stem 6, with the center hole in the bottom of the outer bowl in register with the screw threaded top hole in the adjacent end portion of the base stem, after which the inner bowl 30 is screwed into place with its projected central nipple member 29 inserted in said top hole of the base stem 6. By the same token and reversal of operation, the parts are disassembled with equal ease and facility.

When the pipe is being smoked, smoke is drawn downwardly through the nipple 29 from the bowl 30 and into the first longitudinal channel 11 and continues along the passages described above.

Removal of the plug 23 permits cleaning of the trap chamber 21, and, in fact, the entire base stem and bit or mouth piece assembly. The removability of the bowl assembly 5 also facilitates cleaning and repairing of the entire pipe structure. The plug 23 will prevent loss of the bowl off the rear end of the base stem in the event of a fracture or failure of the nipple 29.

A modification of the invention is shown in Figure 5 wherein the reference character 36 denotes an internally screw threaded hollow base stem of a cigarette holder, the same having a cigarette-receiving socket 37 at one end. At the inner end of the socket 37 is a venturi throat opening 38 communicating with a flared space 39 at the adjacent end of the screw threaded bore of the base stem 36. In this modification there is a bit or mouth piece 40 similar, in general, to the bit or mouthpiece 7 of the hereinbefore described pipe construction, except that there is no trap for nicotine-laden moisture. That is to say, the mouthpiece proper 40 has an externally screw threaded nipple extension 41 provided with smoke duct grooves 15' and 17' in an arrangement substantially like that of the grooves 15 and 17 of the above-described structure. Said nipple extension 41 is also provided with partially circumferential smoke duct grooves 11' extending longitudinally therethrough from the end thereof and terminating at a point adjacent its opposite end. The grooves 11', 15' and 17' are cross-connected, as at 13', 14' and 16', substantially in the same manner so as to afford a longitudinal back and forth travel of the smoke. The nipple extension 41 is readily screwed into the bore of the base stem 36 in assembling the parts, and

it is as readily removed, at will, for the cleaning and repair of the parts.

While the foregoing specification sets forth the invention in specific terms, the recited structure is merely illustrative of a practical exemplification of the invention, and it is to be understood that numerous changes in the shape, size of the parts and also as to the material used, may be resorted to without departing from the spirit and scope of the invention as hereinafter claimed.

Having described the invention, what is claimed as new is:

1. As a new article of manufacture, a smoking pipe including a hollow base stem having one end provided with a mouthpiece and a bowl detachably secured to the other end thereof, said base stem being provided with a longitudinally extending bore, there being opposed grooves extending from the other end of said base stem, tongue means carried by said bowl and slidably supported within said opposed grooves for assembling said bowl on said base stem, connecting means dependently supported by said bowl and connected to said base stem for positioning said bowl with respect to said base stem, said connecting means having one end in communication with said bowl and having the other end in communication with said bore, and closure means positioned adjacent to said other end of said base stem and threadably secured to said bore for closing the latter and to prevent said bowl from being inadvertently slid off the end of said base stem.

2. As a new article of manufacture, a smoking pipe including a hollow base stem having one end provided with a mouthpiece and a bowl de-

tachably secured to the other end thereof, said base stem being provided with a longitudinally extending interiorly threaded bore, there being opposed grooves extending inwardly from the other end of said base stem, tongue means carried by said bowl and slidably supported within said opposed grooves for assembling said bowl on said base stem, a screw threaded nipple member having one end connected to said bowl member and having the other end extending through and embracingly supported within said base stem for positioning said bowl with respect to said base stem, said nipple member having one end in communication with said bowl and having the other end in communication with said bore, and closure means positioned adjacent to said other end of said base stem and threadably secured to said bore for closing the latter and to prevent said bowl from being inadvertently slid off the end of said base stem.
